OPERATING APPARATUS FOR CURRENT COLLECTORS

Walter Achenbach, Hennigsdorf, and Rudolf v. Tempelhoff, Tegel, Germany, assignors to General Electric Company, a corporation of New York

Application February 21, 1939, Serial No. 257,618
In Germany June 11, 1938

5 Claims. (Cl. 191—49)

The present invention relates to apparatus for operating current collector shoes of electric railway vehicles. Although the invention is not necessarily limited thereto, it is particularly adaptable for use with railway vehicles which are operated in third rail systems.

It is desirable that current collector shoes of electric railway vehicles be so arranged that they are capable of being moved to the operative position in engagement with the current carrying conductor or to a disengaged or inoperative position. The operating mechanism is usually controlled by compressed air, but when the collector shoe has been withdrawn from the third rail for a length of time, the supply of compressed air may have become exhausted or diminished to such an extent that the shoe cannot be operated again by its associated mechanism into engagement with the third rail. For such situations, a hand pump must be provided for building up suitable operating pressure or else it is necessary to provide an auxiliary source of electric power in the form of batteries for operating the compressor motor.

It is an object of this invention to provide a new and improved arrangement for operating either manually or automatically a current collecting shoe of an electric railway vehicle.

It is a further object of this invention to provide a new and improved arrangement for operating a current collecting shoe of a railway vehicle by either manual or remote controlled means, the arrangement being so organized that the control may be transferred from manual to power operated means in a simple and efficient manner.

In accordance with the illustrated embodiment of this invention, a new and improved arrangement is provided whereby the current collecting shoe is operable either manually or by remote controlled means. When operated manually against the third rail, the shoe is latched in position, but the latch mechanism is automatically released upon the energization of the remote controlled operating elements which thereafter control the positioning of the shoe.

For a consideration of what we believe to be novel and our invention, attention is directed to the following description and the claims appended thereto taken in connection with the accompanying drawing.

In the drawing, Fig. 1 is a diagrammatic representation of a current collecting shoe operating mechanism embodying the invention and shown in the inoperative or disengaged position; Fig. 2 is a sketch illustrating the apparatus in the operative or the engaged position of the shoe with respect to the third rail; and Fig. 3 is a sketch illustrating the operation of one detail of the apparatus.

Referring to the drawing, a current collecting shoe 10 is mounted on the end of an arm 11 which is pivotally secured as at 12 to the railway vehicle (not shown) and adapted to be moved into engagement with the current carrying conductor or third rail 13. An extension of the arm 11 projecting beyond the pivot 12 is connected as by the tension spring 14 to an operating lever 15, the operating lever 15 being rigidly connected to the shaft 16 which is also provided with rigidly connected levers 17, 18 and 19. The shaft 16 is adapted to be operated either manually by means of a handle 20 or by means of the motor 21 as will be described. The shaft 22 which may be mounted coaxially with the pivot 12 and 15 adapted to be operated by a handle 20 is provided with a rigidly connected lever 23 which in turn is connected by means of the link 24 with the lever 18. Upon the movement of the handle, applied onto the end of the shaft 22, in the clockwise direction, the shaft 16 will be similarly rotated moving the upper end of the shoe carrying arm 11 to the right bringing the shoe 10 into engagement with the third rail 13 as shown in Fig. 2. Because of the tension spring connection between the lever 15 and the arm 11, the shoe will be held resiliently against the third rail so as to compensate for normal shifting movements between the vehicle and the third rail during the operation of the vehicle. It will be noted that the mechanism is retained in the position shown by the latch 25 which engages the end of the lever 19, the latch being normally biased to an operative position by spring 26. Upon either manual or automatic tripping of the latch 25, the lever 19 and the operating lever 15 will be moved to the inoperative position by means of the spring 27 arranged between the lever 17 and a stationary part 28. Upon the resultant rotation of the shaft 16 in the counter-clockwise direction, the link 24 will be moved toward the left rotating the lever 23 also in the counter-clockwise direction. The offset arm 29 fixed with respect to the lever 23 is adapted to engage with the upper end of the arm 11 so as positively to move the arm and hence the shoe to the inoperative or disengaging position.

Once the shoe is moved into engagement with the third rail 13 by the hand operated lever and power is available within the vehicle, the control of the shoe may be transferred to the motor operating mechanism. Although any suitable type of remote controlled motor may be embodied for operating the shoe, the motor shown in this instance is a compressed air driven servo-motor, the piston of which is connected by the stem 29 to the lever 17. Compressed air may be supplied to the motor 21 through the conduit 30, the control valves therefor (not shown) may be of any suitable type. Simultaneously with the energiza-

tion of the motor 21, latch 25 is actuated to the inoperative position. In the embodiment shown, an auxiliary compressed air motor 31 is provided having a piston connected by stem 32 to an arm 33 associated with the latch 25. In order to insure that the latch will not be tripped until ample pressure is built up within the motor 21 for holding the shoe in engagement with the third rail, means are provided for delaying the action 10 of the auxiliary motor 31. Such means may be a restriction or an orifice 34 provided in the conduit 35 adjacent the motor 31 for limiting the rate of air supply thereto. The energized condition of the motor 31 and the corresponding position 15 of the latch 25 is illustrated in the detail sketch Fig. 3. The orifice 34 also serves for delaying the return of the latch 25 to the operative position under the action of the spring 26 when, during remote control, the pressure is released in the conduit 30 for retracting the shoe. At such 20 time the piston of the motor 21 will be forced downwardly under the action of the spring 27 and the shaft 16 rotated in the counterclockwise direction. The fluid in the cylinder of the motor 31, however, will leak out slowly due to the orifice 34 whereby the return of the latch 25 to the operative position will be delayed until such time as the end of the lever 19 will be moved clear.

Having described the principle of operation of 30 our invention together with the apparatus which we now consider to represent the best embodiment thereof, we desire to have it understood that the apparatus shown is only illustrative and that the invention may be carried out by other 35 means.

What we claim as new and desire to secure by Letters Patent of the United States is:

1. The combination, a contact adapted to be moved into engagement with a conductor, a pivoted arm carrying said contact, an operating lever, resilient tension means connecting said lever and said arm, manually operable means for actuating said lever to an operative position effecting engagement of said contact with the conductor by the tensioning of said connecting means, spring means operably associated with said operating lever biasing it to the inoperative position, a latch for retaining said operating lever in the manually actuated operative position, a 40 motor for actuating said operating lever to the operative position, an auxiliary motor adapted to be energized upon the energization of said actuating motor for adjusting said latch to an inoperative position and means for precluding the 45 operation of said latch by said auxiliary motor until said actuating motor is in its fully energized condition.

2. The combination, a contact adapted to be moved into engagement with a conductor, a pivoted arm carrying said contact, an operating lever, resilient means connecting said lever and said arm, manually operable means for actuating said lever to an operative position effecting engagement of said contact with the conductor, 50 spring means operably associated with said operating lever biasing it to the inoperative position, a latch for retaining said operating lever in the manually actuated operative position, a motor for actuating said operating lever to the operative 55 position, an auxiliary motor adapted to be energized upon the energization of said actuating motor for adjusting said latch to an inoperative position and means for delaying the operation 60

of said auxiliary motor upon the energization and deenergization of the actuating motor.

3. Apparatus for operating a shoe for collecting current from a third rail, said apparatus comprising a pivoted arm for carrying said shoe into engagement with said third rail, an operating lever for said arm, resilient means connecting said lever and said arm, manually operable means for actuating said lever to an operative position effecting engagement of said shoe with said third rail, spring means operably associated with said operating lever biasing it to the inoperative position, a latch normally biased to an operative position for retaining said operating lever in the manually actuated position, a motor for actuating said operating lever to the operative position, and an auxiliary motor adapted to be energized upon the energization of said actuating motor for moving said latch to an inoperative position while said operating lever is maintained in said operative position by said actuating motor.

4. Apparatus for operating a shoe for collecting current from a third rail, said apparatus comprising a pivoted arm for carrying said shoe into engagement with said third rail, an operating lever, resilient means connecting said lever and said arm whereby said shoe is resiliently held in engagement with said third rail upon the actuation of said operating lever to the operative position, positively acting means for causing the disengagement of said shoe from said third rail upon the actuation of said operating lever to the inoperative position, manually operable means for actuating said operating lever to the operative position, spring means connected to said operating lever biasing it to the inoperative position, a latch for retaining said operating lever in the manually actuated operative position, a fluid pressure motor for actuating said operating lever, an auxiliary fluid pressure motor means adapted to be energized with the energization of said actuating motor for moving said latch to the inoperative position only after the fluid pressure in said actuating motor is sufficient for holding said operating lever in said operative position.

5. Apparatus for operating a shoe for collecting current from a third rail, said apparatus comprising a pivoted arm for carrying said shoe into engagement with said third rail, an operating lever, resilient means connecting said lever and said arm whereby said shoe is resiliently held in engagement with said third rail upon the actuation of said operating lever to the operative position, positively acting means for causing the disengagement of said shoe from said third rail 55 upon the actuation of said operating lever to the inoperative position, manually operable means for actuating said operating lever to the operative position, spring means connected to said operating lever biasing it to the inoperative position, a latch for retaining said operating lever in the manually actuated operative position, a main fluid motor for actuating said operating lever, an auxiliary fluid motor for adjusting said latch to the inoperative position, said fluid motors adapted to be energized substantially simultaneously, and means restricting the flow of operating fluid to and from said auxiliary motor for delaying the operation of said auxiliary motor upon the energization and deenergization of said 70 main fluid motor.
